UNITED STATES PATENT OFFICE.

GUSTAV BERNHARD PETSCHE, OF PHILADELPHIA, PENNSYLVANIA, AS
SIGNOR TO THE SOUTHWARK FOUNDRY & MACHINE COMPANY, OF
SAME PLACE.

STEAM-ENGINE FOR AIR-COMPRESSORS.

SPECIFICATION forming part of Letters Patent No. 670,810, dated March 26, 1901.

Application filed July 31, 1897. Serial No. 646,636. (No model.)

To all whom it may concern:

Be it known that I, GUSTAV BERNHARD PETSCHE, a subject of the Emperor of Germany, residing in the city and county of Philadelphia, in the State of Pennsylvania, have invented a certain new and useful Improvement in Steam-Engines for Air-Compressors, of which the following is a true and exact description, reference being had to the accompanying drawings, which form a part thereof.

My invention relates to the construction and operation of steam-engines, particularly to steam-engines forming a part of what is known as a "blowing-engine"—that is to say, operating a piston of an air-compressing cylinder.

A prime object of my invention is to provide for the actuation and control of both the steam and air valves of the engine from a single eccentric, thereby greatly simplifying the construction of the machine and diminishing its cost.

Further objects are an improvement in the mechanism for actuating the rotary or, as they are generally called, "Corliss" valves of the steam-engine, to provide an improved mechanism especially designed for facilitating the operation of the steam-valves by hand in starting the engine, and to provide an efficient and simple device for regulating the opening of the air-admission valve, so as to insure that it shall open substantially at the point where the pressure in the cylinder is equal to the atmospheric pressure, this device being provided to meet the contingency of the engine running at different times under different air-pressures.

The nature of my improvements will be best understood as described in connection with the drawings in which they are illustrated, and in which—

Figure 1 is a front elevation of the steam-cylinder part of the engine, illustrating particularly the novel features of construction in connection with the steam-valve-actuating mechanism. Fig. 2 is a side elevation of the engine as a whole, illustrating particularly the construction of a link operated by

a single eccentric and the various valve-actuating connections operated thereby. Fig. 3 is a cross-sectional view on the line 2 2 of Fig. 2. Fig. 4 is a cross-sectional view on the line 1 1 of Fig. 2. Fig. 5 is an elevation showing the admission-air-valve-actuating cam. Fig. 6 is a sectional elevation showing the construction of the actuating-cylinder which moves the air-delivery valve. Fig. 7 is a diagrammatic view illustrating the link-motion, particularly with reference to the adjustment of the opening-point of the air-admission valve; and Fig. 8 is a diagram showing an indicator-card, illustrating the action of the compressing-cylinder under different pressures.

A indicates the frame of the engine, B indicating the position of the steam-cylinder.

C is the main crank-shaft, and D D fly-wheels.

E is the tub or air-compressing cylinder in which moves the air-compressing piston. (Illustrated in Fig. 6 and marked E².)

F is the valve-rod by which the delivery-valve of the air-tub is actuated. It is, as shown in Fig. 6, connected to the piston F', moving in a cylinder F², to the front end of which leads the pipe F³, opening into the tub, as indicated at f³.

F⁴ indicates a pipe through which fluid under pressure, preferably steam or air, is led through a port f⁴ into the rear side of the cylinder F².

F⁶ is a valve actuated, as will be herein-after explained, from the eccentric on the main shaft and governing the admission of the pressure fluid from the pipe F⁴ to the cylinder F² and the exhaust from said cylinder into the exhaust-port F⁵.

The device above described is a well-known one for actuating the delivery-valves of blowing-engines and forms no part of my invention, being simply shown as a convenient device for operating the delivery-valve and the one which I have in practice employed in connection with my improvements to be herein-after described.

The connection for operating the pilot-valve F⁶ may be traced in Fig. 2 as follows: f⁶ is a

lever attached to the valve-stem and from it leads a rod f^7 , connecting, through a rock-lever f^8 , a rod F^9 , a bell-crank lever f^9 , rod F^{10} , and lever F^{11} with a rod O^2 , which in turn connects with a slide O , actuated by a link O^3 , connected in its turn to the long arm P' of the link $P' P^2$, which link is operated by an eccentric P and is pivoted on a sliding block P^3 , moving in a guide P^4 .

10 G indicates the valve-stem of the air-admission valve of the blowing-tub and has attached to its end a cam G' , in which works a cam-roller g^3 , attached to one end of the rock-lever G^3 , the cam working, as indicated, in guides G^2 and the rock-lever being actuated, as shown, through the rod G^4 , rock-lever G^5 , and the rod G^6 , which is attached to the point Q^3 on a lever Q^2 , said lever being pivoted at one end to the slide Q , adjustably toward and away 15 from the link $P' P^2$ by means of an adjusting-screw Q' . The other end of the link Q^2 is pivoted at q^2 and the link Q^4 , which in turn is pivoted to the short arm P^2 of the link, operated by an eccentric.

20 25 It will readily be understood how the motion of the eccentric-link communicates motion through the cam to the air-inlet valve; but with the exception of the adjustability of the device I do not claim the mechanism shown as an invention, except in so far as it forms a part of the general combination by which the single eccentric is made to operate all the valves of the engine. If, however, the stroke of the point Q^3 , to which the valve-actuating connections are connected, were constant, the air-valve would always open at the same point with respect to the motion of the main crank, and this might in some cases be too soon and in other cases too late. If too 30 soon, the air compressed in the head of the tub would escape on the opening of the air-valve, and if too late the air in the head of the tub would fall below atmospheric pressure before the valve opened, and in both cases 35 a loud and objectionable noise occurs by reason of the outrush or inrush of the air. The proper point, as already stated, for the opening of the inlet-valve is when the air in the head of the tub is at atmospheric pressure; 40 but supposing that the engine is at one time at fifteen pounds, at another time at thirty pounds, and at another time at forty pounds the diagram Fig. 8 illustrates the different points with regard to the total stroke of the 45 piston at which the valve should open. In this diagram the line $X X$ indicates the total stroke of the compressing-piston, the lines 15, 30, and 40 form in each case the top of the card, and the points 3, 1, and 2 indicating the 50 various points with reference to the piston-stroke at which the admission-valve should open.

55 Referring now to the diagram Fig. 7, it will be seen how by adjusting the slide Q the 60 desired variation in the opening-point of the admission-valve can be obtained. Figs. 1, 2, and 3 used in this diagram correspond with

Figs 1, 2, and 3 in diagram Fig. 8, and the points so numbered on the closed curve indicating the motion of the point on the end P^2 of the link, to which link Q^4 is attached, indicating the various points at which the valve will open for the different adjustments of the slide Q to the points similarly numbered.

70 75 Referring next to Fig. 1 of the drawings, the valves, the positions of which are indicated by the symbols $H I$, are of the rotary type, $H H$ indicating the exhaust-valves and $I I$ the admission-valves. The exhaust-valves have connected with their stems lever H' , which is connected by links H^2 with the slides $N N'$, which slides are permanently secured together and move as one. The admission-valves have attached to their stems lever-arms I' , having at their outer ends a hook-engaging edge i' of the general character common in the so-called "Corliss" valve. Loosely pivoted on the valve-stems of the admission-valves are the idler-levers J' , having attached 80 to the ends of one of their arms hooks K , adapted to engage the levers I with their edges K' , and having at their outer ends fingers K^2 , preferably extending outward, as shown. K^3 indicates springs for pressing the hooks inward, so as to insure their engaging with the valve-actuating lever. To the other arms of the idler-levers are pivotally connected the hook-lifting levers $L L'$, the short arm L of which lies beneath and in operative relation 85 with the finger K^2 of the hook, while the long arm L' extends in toward the center of the valve-stem with which its point of adjustment to its actuating-rod should practically coincide. Each idler-lever is given an oscillatory movement from the slide N or N' through a link I^2 , with the result of engaging 90 its hook with the corresponding valve-lever I at each stroke and acting on the valve to open it through a portion of the stroke of the idler-lever determined by the action of the 95 hook-lifting lever, which at a proper time lifts the hook out of engagement with the valve-lever, whereupon the valve is promptly closed by the usual mechanism tending to draw it 100 back or in opposition to the direction in which it is carried by the hook.

105 110 The special advantages of the above-described valve-actuating apparatus are those incident to the new construction by which a hook and hook-lifting lever are attached to separate arms of an idler-lever and arranged in such wise that the hook-lifting lever, acting with a powerful leverage, engages the outer end of the hook, thereby having the 115 maximum power to lift the hook and insuring a prompt disengagement of the valve.

120 125 As already stated, the slides N and N' are secured together and move as a single slide. In operation the slide N is coupled to the 130 slide O and moved by it and practically as a part of it by the engagement of the latch N^3 passing through the perforation N^2 in the slide N' with a latch-detent O' , formed in the

slide O. The two slides are disconnected by drawing out the latch N³ by means of a handle N⁴, and then by turning said handle a locking-pin N⁵ is brought out of register with the slot, as indicated, and so as to lie across the top of the box N⁶, holding the latch out of engagement with the slide O. On returning the handle N⁴ a spring N⁷ in the box N⁶ presses the latch in, and as soon as it again registers in the recess O' the three slides are again coupled. The disengagement of the slide N from the slide O is chiefly usual when it is necessary to start the engine. A socket-lever S² S', pivoted at S³, connecting with the slide N by a link S, enables the engineer to insert a handle S⁴ in the socket and move the slides N and N' by hand to actuate the valves and start the engine, which after the slides N and O are latched together automatically operates its own valves.

Returning again to the hook-lifting levers and referring first to Fig. 1 of the drawings, it will be seen that each lever-arm L' is connected by a link M to one arm M' or m' of a T-lever, the third arm of which is indicated at M² and which lever is pivoted to the rock-lever M³, the said rock-lever being given a constant and regular reciprocation by being connected with the link R², (see Fig. 2,) in turn connecting to the bell-crank lever R' and link R with the slide-block P³ of the eccentrically-operated link P' and P².

Obviously by shortening or lengthening the distance between the ends of the links M M', which engage the long arms of the hook-lifting levers, the said levers will act at an earlier or later stage upon the hooks, thereby varying the cut-off of the steam-admission valves. This operation is performed by movements of the T-lever M' m' M², regulated by the governor of the engine. Thus, as shown, the arm M' of the T-lever connects, through a lever-link M⁴, bell-crank M⁵, link M⁶, and link M⁹, with the governor indicated at M¹⁰, and proper motion being secured by attaching the link M⁶ also to the rock-lever M⁵, M⁸ indicating regulating device.

Having now described my invention, what I claim as new, and desire to secure by Letters Patent, is—

1. In a steam-engine the combination with a rotary valve of a lever I' secured to the stem, an idler-lever J' pivoted upon the valve-stem and oscillated by a positively-moving part of the engine, a hook K pivoted upon one arm of the idler-lever J' and arranged to engage and operate valve-lever I' said hook having a finger K², a hook-lifting lever L L' pivoted to the other arm of the idler-lever and having its short arm L arranged in operative position to engage finger K² of the hook and means for intermittently operating the hook-lifting lever controlled by a governor.

2. In a steam-engine the combination with a rotary valve of a lever I' secured to its stem, an idler-lever J' pivoted upon the valve-

stem and oscillated by a positively-moving part of the engine, a hook K pivoted upon one arm of the idler-lever J' and arranged to engage and operate valve-lever I' said hook having a finger K², a hook-lifting lever L L' pivoted to the other arm of the idler-lever and having its short arm L arranged in operative position to engage finger K² of the hook and its long arm L' normally extending inward so that the connecting-point for its actuating mechanism will correspond substantially with the center of the valve-stem and means for intermittently operating the hook-lifting lever controlled by a governor.

3. In a steam-engine the combination with a rotary valve of a lever I' secured to its stem, an idler-lever J' pivoted upon the valve-stem and oscillated by a positively-moving part of the engine, a hook K pivoted upon one arm of the idler-lever J' and arranged to engage and operate valve-lever I' said hook having a finger K², a hook-lifting lever L L' pivoted to the other arm of the idler-lever and having its short arm L arranged in operative position to engage finger K² of the hook and its long arm L' normally extending inward so that the connecting-point for its actuating mechanism will correspond substantially with the center of the valve-stem, a positively and uniformly moving actuating device as lever M³ an adjustable connection thereon as bell-crank lever M' m' M² operatively connected with lever-arm L' and a connection from said adjustable connection to a governor.

4. In a steam-engine the combination of a positively-moving slide as O actuated by an eccentric and link-motion and supported in guides on the engine with a slide N connecting with and actuating the steam-engine valves, a latch whereby the slides O and N can be secured together or disconnected at pleasure and means as socket-lever S' S² for independently operating slide N to start the engine.

5. In a steam-engine the combination with a rotary valve of a lever I' secured to its stem, an idler-lever J' pivoted upon the valve-stem and oscillated by a positively-moving part of the engine, a hook N pivoted upon one arm of the idler-lever J' and arranged to engage and operate valve-lever I' said hook having a finger K², a hook-lifting lever L L' pivoted to the other arm of the idler-lever and having its short arm L arranged in operative position to engage finger K² of the hook and its long arm L' normally extending inward so that the connecting-point for its adjusting mechanism will correspond substantially with the center of the valve-stem, a positively and uniformly moving actuating device as lever M³ an adjustable connection thereon as bell-crank lever M' m' M² operatively connected with lever-arm L' and a connection from said adjustable connection to a governor, a link P' P² pivoted on a slide P³ and actuated by an eccentric P, a connection

from the arm P' of the link to actuate the idler-lever J' and a connection from the slide P^3 to actuate the lever M^3 substantially as shown and described.

5. In a steam-engine for actuating an air-compressor and having an eccentric P , the combination of a link $P' P^2$ actuated by the eccentric a slide O coupled to the end P' of the link and to a pilot-valve controlling the

10 action of the air-delivery valve of the compressing-cylinder, a slide N secured in guides so as to lie side by side with slide O , a latch whereby said slide N can be coupled or uncoupled with slide O valve-actuating mechanism for the steam-cylinder actuated by slide N and means as socket-lever $S' S^2$ for operating slide N by hand to start the engine.

7. In a steam-engine for actuating an air-compressor and having an eccentric P the 20 combination of a link $P' P^2$ pivoted on a slide P^3 and actuated by the eccentric a slide O coupled to the end P' of the link and to a pilot-valve controlling the action of the air-delivery valve of the compressing-cylinder,

25 a slide N secured in guides so as to lie side by side with slide O , a latch whereby said slide N can be coupled or uncoupled with slide O , rotary steam-valves for the steam-cylinder, an idler-lever J' actuated by slide N and carrying a hook and hook-lifting lever as described, a connection from the slide P^3 of the link arranged to actuate the hook-lifting lever and a governor arranged in the hook-lifting mechanism to vary the cut-off as specified.

30 35 8. In a steam-engine for actuating an air-compressor and having an eccentric P , the combination of a link $P' P^2$ pivoted on a slide P^3 and actuated by the eccentric, steam-valve-

actuating mechanism connected with the arm P' of the link $P' P^2$, a link Q^4 pivoted at one 40 end to the arm P^2 of the link $P' P^2$, a slide Q arranged to be adjusted toward and away from the link P', P^2 , a link Q^2 pivoted to said slide and to the free arm of link Q^4 and a valve-actuating connection extending from a 45 point on links Q^2 or Q^4 to the air-admission valve or valves of the compressing-cylinder.

9. In a steam-engine for actuating an air-compressor and having an eccentric P the combination of a link $P' P^2$ pivoted on a slide 50 P^3 and actuated by the eccentric, a slide O coupled to the end P' of the link and to a pilot-valve controlling the action of the air-delivery valve of the compressing-cylinder, a slide N secured in guides so as to lie side 55 by side with slide O , a latch whereby said slide N can be coupled or uncoupled with slide O , rotary steam-valves for the steam-cylinder, an idler-lever J' actuated by slide N and carrying a hook and hook-lifting lever as described, a connection from the slide P^3 of the link arranged to actuate the hook-lifting lever, a governor arranged in the hook-lifting mechanism to vary the cut-off as specified, a link Q^4 pivoted at one end to the arm P^2 of 60 the link $P' P^2$, a slide Q arranged to be adjusted toward and away from the link $P' P^2$, a link Q^2 pivoted to said slide and to the free end of link Q^4 and a valve-actuating connection extending from a point on links Q^2 or Q^4 65 to the air-admission valve of the compressing-cylinder.
